UNITED STATES PATENT OFFICE.

WILLIAM W. PATTERSON, OF MURRAYVILLE, ILLINOIS.

SCOOP-BOARD FOR VEHICLE-BODIES.

SPECIFICATION forming part of Letters Patent No. 718,019, dated January 6, 1903.

Application filed January 20, 1902. Renewed December 8, 1902. Serial No. 134,439. (No model.)

To all whom it may concern:

Be it known that I, WILLIAM W. PATTERSON, a citizen of the United States, residing at Murrayville, in the county of Morgan and 5 State of Illinois, have invented certain new and useful Improvements in Scoop-Boards for Vehicle-Bodies; and I do declare the following to be a full, clear, and exact description of the invention, such as will enable others skilled in the art to which it appertains to make and use the same.

The invention relates to a scoop-board for vehicle-bodies, and embodies in its construction an end-gate which is pivoted or hinged 15 in the usual manner to the end of the vehicle-box and which is provided with wings which will close the space between the end-gate and the side pieces of the vehicle-box when said end-gate is lowered a certain distance, and thereby prevent the escape of the 20 contents of the vehicle-box. The end-gate is constructed with a centrally-located hinged panel, whereby access to the vehicle-box may be obtained without the necessity of lowering 25 the end-gate.

The object of the invention is to provide a device of this character which shall be simple of construction, durable in use, and comparatively inexpensive of production.

With this and other objects in view the invention consists of certain novel features of construction, combination, and arrangement of parts, which will be hereinafter more fully described, and particularly pointed out in the 35 appended claim.

In the accompanying drawings, Figure 1 is a perspective view of a wagon-box, illustrating the application of the invention. Fig. 2 is a longitudinal vertical sectional view showing in dotted lines the panel swung upwardly.

Fig. 3 is a similar view showing the end-gate used as a scoop-board, and Fig. 4 is a transverse fragmentary section on line xx of Fig. 2.

In the drawings, 1 denotes a wagon-box, and 45 2 an end-gate hinged at its lower end to the rear end of the wagon-box and provided with side wings 3, which serve to prevent the contents of the box from falling out when said end-gate is lowered into position for use as a 50 scoop-board. Chains 4 or other suitable means are employed for holding the end-board

in closed or adjusted position, the inner ends of said chains being connected by staples 5 to the sides of the wagon and the other ends being provided with hooks which pass through 55 the staples 9, secured to the wings. The end-gate is provided centrally with an opening, which is closed by a panel 10. This end-gate is provided with strengthening cross-bars 11 and 12 and the panel with a cross-bar 13. 60 Hinges 14 connect the cross-bars 11 and 13 and permit of the panel being swung upwardly to obtain access to the wagon-box when it is desired and after unfastening the chains allow the end-gate to swing downwardly. Any suitable 65 means may be employed for holding the panel in its elevated position. For instance, I may provide the panel with a stud 15, which is adapted to coact with the spring-catch 16, secured to the end-gate near its upper end, 70 and when said panel is elevated this catch will hold it in that position. When the panel is in closed position, it may be held in any suitable manner—as, for instance, by providing the end-gate adjacent to the side walls 75 of the opening with spring-catches 17, which are adapted to engage wear-plates 18, secured to cross-bars 19, carried at the lower end of the panel. Short cross-pieces 19' are secured to the end-gate and form a continuation of 80 the cross-piece 19 and have their inner ends formed with notches or recesses 20 to allow an outward or lateral yielding movement of the spring-catch when the panel is swung downwardly in closed position.

From the foregoing description, taken in connection with the accompanying drawings, the construction, mode of operation, and advantages of the invention will be readily understood without requiring a more extended 85 explanation.

Various changes in the form, proportion, and details of construction may be made within the scope of the invention without departing from the spirit or sacrificing any of 95 the advantages thereof.

Having thus described my invention, what I claim, and desire to secure by Letters Patent, is—

As an article of manufacture, an end-gate 105 for wagons adapted to be hinged at its lower end to the box of the wagon, said end-gate

comprising the following essential elements: | to hold the panel in closed position, substantially as set forth.
a panel constituting a portion of the end-gate and hinged to the upper end thereof, wings fixed to the sides of the end-gate, a fixed stud 5 carried by the panel near its upper end, a spring-hook carried by the upper end of the end-gate and adapted to engage the stud and hold the end-gate in open position, and spring-catches carried by the end-gate and adapted

In testimony whereof I have hereunto set my hand in presence of two subscribing witnesses.

WILLIAM W. PATTERSON.
